UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

TERMINAL CONNECTING DEVICE.

Application filed April 19, 1921 Serial No. 462,728.

The present invention relates to certain new and useful improvements in terminal connecting devices adapted to connect the conductors of electric circuits.

The use of electrical apparatus in coal mines is accompanied by more or less danger of explosion arising from the possibility of the ignition of the gas charged atmosphere of the mine by the electric arcs occurring at contact points of the apparatus, or by the flashes produced by accidental short circuiting the conductors of the circuits. To reduce this explosion hazard to a minimum, explosion proof casings have been devised for the motors, switches, and similar devices the normal operation of which is accompanied by the production of electric arcs, and the conductors extending from one such protected device to another are encased in the customary electric insulations to which is added an armor composed of metal or other suitable material of approved mechanical strength.

The especial object of this invention is to provide a conveniently detachable connecting device adapted to connect the conductors of the external circuit with the conductors of the circuit within an explosion proof casing, combined with means for insuring the electrical insulation and mechanical protection of said connecting devices.

The means by which I attain this object are fully set forth in the following specification and illustrated in the accompanying drawings of which

Fig. 1 is a sectional view taken along the central longitudinal plane of the preferred embodiment of my invention.

Fig. 2 is a cross sectional view taken along the line II—II of Fig. 1.

Like numerals refer to similar parts in both figures.

In the drawing the numeral 1 indicates a portion of the wall of the explosion proof casing of an electric motor adapted to use upon an electric locomotive or other machine in the gas charged atmosphere of a coal mine. 2 indicates a conductor extending from the electric circuits within the casing through the aperture 3 for connection with the conductors of the external circuit. Suitable electric insulation 4 surrounds the conductor 2 to protect it from contact with the casing 1 in the manner well understood in the art. The outer end of the conductor 2 is attached,

in any preferred manner such as by soldering, to one end of a two part connector 5, the parts of which are secured together in any preferred manner such as by the machine screws 6. To the opposite end of the connector 5 is attached the conductor 7 of the external circuit. The conductor 7 is protected by the usual electrical insulation 8 which in turn is protected by the flexible metal conduit 9 of well known construction which may be securely attached to the metallic frame of the machine in any preferred manner.

The aperture 3 of the motor casing is counterbored at 10 and in this counterbore is screw threaded a tubular shield 11 of somewhat larger diameter than the connector 5. The outer end 12 of the shield 11 is contracted to fit snugly around the flexible metallic conduit 9 to the end of which is soldered, or otherwise secured, a ring 13 arranged to engage the inner face of the contraction 12 to prevent accidental separation of the conduit 9 and the shield 11. Spacing washers 14, formed of fiber or other suitable insulating material, and having an external diameter approximately equal to the internal diameter of the shield 11, are fitted snugly upon the insulations 4 and 8 in close proximity to the ends of the connector 5 to insure its central position within the shield. The connector 5 is further protected by an insulation 15, formed of friction tape or other suitable material, to guard against possible short circuit between the connector 5 and the shield 11.

By the arrangement of parts just described the flexible metallic conduit 9 is securely connected to the motor casing 1 and the insulation of the connector 5 is fully protected from mechanical injury while these parts are in operative position, and the conduit 9 and conductor 7 may be conveniently disconnected from the motor to allow its removal from the machine.

What I claim is:

1. In a conduit for electric wires, the combination of a casing, a conductor projecting therefrom, a tubular metallic shield fixed to said casing and surrounding said conductor, an armor-sheathed conductor detachably connected to said first conductor within said shield, the free end of said shield being closed about said second conductor, a ring fixed to the armor-sheathing of said second

conductor within said shield and abutting the internal shoulder formed by the closed end of the latter, and insulating means extending beyond the periphery of said conductors for maintaining their zone of juncture in spaced relation to the inner walls of said shield.

2. In a conduit for electric wires, the combination of a casing, a conductor projecting therefrom, a tubular metallic shield fixed to said casing and surrounding said conductor, an armor-sheathed conductor detachably connected to said first conductor within said

shield, the free end of said shield being closed about said second conductor, a ring fixed to the armor-sheathing of said second conductor within said shield and abutting the internal shoulder formed by the closed end of the latter, and insulating annuli surrounding the conductors within the shield and at either end thereof for maintaining the zone of juncture of said conductors in spaced relation to said shield.

In testimony whereof, I affix my signature.

NILS D. LEVIN.
